UNITED STATES PATENT OFFICE.

HAROLD V. McCORMICK, OF CINCINNATI, OHIO, ASSIGNOR TO THE WARNER ELEVATOR MANUFACTURING COMPANY, OF CINCINNATI, OHIO, A CORPORATION OF OHIO.

ELECTRICAL BRAKE.

Application filed February 25, 1924. Serial No. 695,123.

An object of my invention is to provide an electrical brake wherein fluid means may be employed for retarding the otherwise rapid movement of the armature associated with 5 such brake apparatus.

Another object of my invention is to provide a structure wherein the fluid retarding means becomes an integral part of the armature for eliminating vibration between them.

10 Another object of my invention is to provide a structure that will effect a slow movement of release and a rapid movement of operation without the use of check valves or other means of changing the effect of fluid 15 flow from the fluid armature retarding means.

Another object is to provide means for clamping the laminations of a laminated steel electromagnetic field and armature for 20 securing the laminations against all lateral movement.

Another object of my invention is to provide a simple and efficient device for the purposes as stated.

25 These and other objects are attained by means described herein and disclosed in the accompanying drawings, in which:

Fig. 1 is a side elevation of the device embodying my invention.

30 Fig. 2 is a sectional view on line 2—2 of Fig. 1.

Fig. 3 is an elevation of an electromagnet core forming a detail of my invention.

Fig. 4 is an elevation showing at right 35 angles thereto, the structure disclosed in Fig. 3.

Fig. 5 is a sectional view on line 5—5 of Fig. 3.

Fig. 6 is an enlarged detail view of an 40 armature forming a detail of my invention.

Fig. 7 is a sectional view on line 7—7 of Fig. 6.

Figs. 8 and 9 are diagrammatic views of 45 wirings or coils forming details of my invention.

The base 20 may be mounted on any suitable foundation 21 in any suitable manner, for example as shown, and may be bolted thereto. The base 20 supports a casing 22.

50 The casing 22 comprises spaced sides 23 and

24. The sides are provided with openings 25 therethrough and a shaft 26 extends through said openings. The shaft 26 carries a drum 27 upon which brake shoes 28 and 29 may operate. The brake shoes are 55 mounted in substantially the same manner wherefore a description of one will suffice for both. The brake shoe 28 is pivotally mounted upon the lower end of an arm 30. The arm 30 is pivotally mounted intermediate its ends upon the sides 23 and 24 by means of a suitable shaft 31. The arm, intermediate the shaft 31 and the upper end of the arm, is provided with a threaded bore 32 through which a screw 33 extends. The 60 inner end of the screw engages a spring cup 34 in abutment upon one end of a spiral spring 35. The second end of the spring 35 engages the casing 22 and is protected from displacement on said casing by providing a boss 36 upon the casing and which boss 65 may enter the center of the spring. A hand lever 37 is provided whereby the screw may be adjusted through the arm 30 for modifying the compression of the spring 35 and 70 consequently modifying the friction whereby the shoe 28 engages the drum. The upper end of the arm 30 is bifurcated, the branches 39 and 40 thereof supporting the pin 38. The pin 38 is pivotally mounted 75 upon the branches 39 and 40 and carries a block 41 from which extends the screw 42. The block is provided with bores 410 any of which will receive pin 38 for adjustment of 80 the lever 44. The U-shaped lever 44 has its one branch 45 adjustably mounted upon the screw 42 and may be secured in adjusted positions by the nut 43. It should be noted 85 that this structure gives a very efficient operating leverage through which the armatures may act upon the brake shoes. The arm 46 of the lever 44 extends through an opening 47 in the cover 48 of the casing 22 and carries a disc like flange 72 that serves 90 as a closure for opening 47. The casing 22 comprises internal ribs or transversely extending walls 49 and 50. The ribs in part are spaced from the bottom 51 of the casing 95 wherefore passages 52 are provided between the chamber 53 at the center of the casing 100

and the chambers 54 and 55 formed in the casing 22 exteriorly of the walls or ribs 49 and 50. The walls 49 and 50 are provided with apertures 56 through which plungers 57 reciprocally extend, whereby a dash pot structure is provided between the plunger and the wall as is disclosed in Fig. 2. The outer end of each plunger 57 is bifurcated and carries a pin 300 on which pin is pivotally mounted the branch 46 of the lever 44. The inner portion of the plunger has mounted upon it a magnet field 58 comprising laminations 59 secured between side plates 60 and 61 by any suitable means such as bolts and nuts 62 and all of which constitutes an armature.

The walls 49 and 50 are provided with inwardly extending flanges 63 and 64 for the reception of the magnet field, the recessed portions of the wall constitutes a retardation cylinder containing the field or armature. The field 58 is actuated by an electromagnet 66 disposed centrally of the casing 22. The electromagnet comprises laminations 67 secured between end plates 68 and 69, which end plates are mounted upon the casing. By reference to Fig. 3 it will be apparent that the core comprising the laminations 67 and end plates is so constructed that 4 notches are provided at the opposite edges of the cores, for the reception of a pair of coils 70 and 71 at both sides of the magnet core. The coils may be electrically connected as shown in Figs. 8 and 9 for effecting any desired phase operation. The casing contains an insulating fluid such as oil and in which fluid the electromagnet and armatures are immersed.

The sides 23 and 24 of the base 20 carry adjustment screws 73 for engagement upon the brake shoes 28 and 29 for limiting the movement of the lower ends of said brake shoes from the drum and for effecting adjustment of the brake shoes to a concentric relationship to the drum and the shaft 26.

The operation of my device is as follows: Normally the electromagnet is deenergized wherefore the brake shoes engage the drum and frictionally resist rotation of the drum. The springs 35 function as the means for effecting this frictional resistance. When the drum is to be released the electromagnet is energized whereupon the armatures or magnet fields are drawn toward the electromagnet thereby moving the arms 30 about their pivotal mountings 31 and moving the brake shoes away from the drum. The dash pot structure or retardation structure, in combination with the proportioning of the levers and the co-acting forces pointed out herein, effects a slow release of the drum. It will be observed that when the drum is released the movement of the armature is resisted both by the springs 35 and the flow of the fluid in the casing. When the electro-

magnet is deenergized the springs 35 return the parts to their normal positions. On de-energization of the electromagnet the springs need overcome only the resistance of the dash pot structure whereby a comparatively rapid movement of application of the brakes is effected. It will be observed that by providing side plates between which the laminations of the field or armature are bolted, all lateral movement of the laminations is precluded. It will be noted that no check valves are required for controlling the flow of fluid in the casing yet a variation in the speeds of application and release of the brake is effected.

Attention is directed to the structures of the armature and magnet core structures. It will be noted that the bolts that secure the laminations do not pass through perforations in the laminations but lie in slots at the edges of the laminations. The slots are of a depth less than the diameters of the bolts wherefore the clamping means are isolated from the area of flux as a result of which heating of the bolts is precluded. This structure also has an advantage in that local actions or closed areas of excitation about the bolts are avoided, thereby eliminating the reduction in general efficiency and avoiding the undesirable local reactions incident to local actions. There is no flow of current through the bolts longitudinally and the presence of the bolts does not distort or modify the normal flux flow through the laminations.

What I claim is:

1. In a device of the class described the combination with a drum, of a brake shoe for frictional engagement with the drum, a lever pivotally mounted intermediate its ends and having the brake shoe mounted at its one end, a U-shaped lever mounted at the second end of the first mentioned lever, yielding means operative upon the first mentioned lever causing the frictional engagement between the drum and the brake shoe, a fluid containing casing, a wall extending transversely of the casing and having a recess formed therein, a flange extending from the wall forming a retardation cylinder, an armature having a rear plate reciprocable through the retardation cylinder and recess and connected with the U-shaped lever, and an electromagnet influencing the movement of the armature and lever in one direction, and the retardation cylinder and recess modifying the action of the yielding means on the brake shoe in the other direction.

2. In a device of the class described the combination of a drum, a brake shoe for frictional engagement upon the drum, means for actuating the brake shoe and means for modifying the action of the brake shoe actuating means, the last mentioned means com-

prising a fluid containing casing having a wall extending transversely of the casing, the wall being provided with a recess, a flange extending from the wall for providing a retardation cylinder, an armature reciprocable in the retardation cylinder and comprising a plate, the plate being recip-

rocable in the recess, the recess and plate forming a dash pot structure whereby the brake shoe actuating means is modified.

In testimony whereof, I have hereunto subscribed my name this 8th day of February, 1924.

HAROLD V. McCORMICK.
